UNITED STATES PATENT OFFICE.

JOHN H. ROBBINS AND SAMUEL ROBBINS, OF BETHEL, OREGON.

IMPROVEMENT IN WHEEL-PLOWS.

Specification forming part of Letters Patent No. 123,294, dated January 30, 1872.

Specification describing Improved Riding-Plow, invented by JOHN H. ROBBINS and SAMUEL ROBBINS, of Bethel, in the county of Polk and State of Oregon.

The invention will first be fully described and then clearly pointed out in the claim.

Figure 1 is a plan; Fig. 2, a front; Fig. 3, a rear view of my improved riding-plow.

A is the pole, on each side of which a horse is to be placed, which is pivoted at *a*, and which is also provided with an end-perforated extension plate, *a*². B is a transverse and recessed socket, attached to a frame, C, and perforated at the points *b*, through which passes bolt *b*'. By changing the position of the tongue laterally, and also the bolt *b*', a greater or less width of furrow may be obtained. D is the plow-beam, having a rigid arm, D¹, and pivoted one D². Near the end is placed the turn-plow E, while at the end and to one side thereof is attached a yoke *d*. This yoke passes over the end of rigid piece D¹, and is provided with a set-screw, *d*', protruding upwardly through the bottom. By causing the screw *d*' to protrude a certain distance through the yoke the sole of the plow will run in a horizontal plane; but when the under side of the point of share becomes dubbed off by attrition the plow has a tendency to run too shallow. In order to overcome this tendency it is necessary to increase the pitch of the plow or to give it a small incline to a horizontal plane. This is easily and quickly accomplished by

slightly withdrawing the screw *d*', and lessening the inclination of piece D¹. F is another yoke, attached to the front of frame C, and apertured at several points on each side. *f* is a pivot-pin, which passes through one of these holes on each side, and laterally through end of beam. G is a lever-frame, fulcrumed in bearings *g* *g*, having extension *g*¹, that is held at various points in a rack-plate, H, and projecting goose-neck *g*², from which is a pendent hook, *g*³. *g*⁴ is a chain attached to the end of rigid piece D¹ of beam. By changing the position of beam, that of front pivot-pin *f*, and hooking the chain *I* at a corresponding point, the horizontal position of the plow is also changed, and it is made to run at a greater or less depth, according to requirement. K is the axle, bent downward to form a central yoke, *k*, whose sides may cause the plow-beam and its plow to be always properly and rigidly aligned.

Having thus described our invention, what we claim as new, and desire to secure by Letters Patent, is—

The adjustable front yoke F and pin *f*, and the lever-frame G *g*², having hook *g*³, combined with beam D D¹ D², having chain *g*⁴; all arranged as and for the purpose described.
